US00D601186S

(12) **United States Design Patent**
Kim et al.

(10) **Patent No.:** **US D601,186 S**
(45) **Date of Patent:** **** Sep. 29, 2009**

(54) **LASER PRINTER**

(75) Inventors: **Hee-Yul Kim**, Kyunggi-do (KR); **Min-Hyoug Boo**, Seoul (KR); **Yun-Gi Hong**, Kyunggi-do (KR); **Byeong-Yong Song**, Kyunggi-do (KR)

(73) Assignee: **Samsung Electronics Co., Ltd.**, Suwon, Kyunggi-Do (KR)

(**) Term: **14 Years**

(21) Appl. No.: **29/294,097**

(22) Filed: **Dec. 21, 2007**

(51) **LOC (9) Cl.** **14-02**

(52) **U.S. Cl.** **D18/55**

(58) **Field of Classification Search** **D18/36-39, D18/50, 54, 54.1, 55; D14/420-425, 462-470; 400/613, 613.1-613.4, 690.1-690.4, 691-694**
